UNITED STATES PATENT OFFICE.

GUSTAF P. WERN, OF NEW YORK, N. Y., ASSIGNOR TO RAWSON & MORRISON MANUFACTURING COMPANY, OF CAMBRIDGEPORT, MASSACHUSETTS, A CORPORATION OF MASSACHUSETTS.

DERRICK-SWINGER.

No. 836,622.

Specification of Letters Patent.

Patented Nov. 20, 1906.

Application filed August 29, 1905. Serial No. 276,223.

To all whom it may concern:

Be it known that I, GUSTAF P. WERN, a citizen of the United States, residing at New

5 York city, in the county and State of New York, have invented certain new and useful Improvements in Derrick-Swingers, of which the following, taken in connection with the accompanying drawings, is a full, clear, and exact specification.

10 My present invention has relation to that class of devices or machines intended for use in swinging derricks or booms and ordinarily known as "derrick-swingers" or "boom-swingers." These machines are usually employed in addition to hoisting-drums or hoisting apparatus for the purpose of swinging the derrick or boom and its load, the raising or lowering of the load being accomplished by the hoisting apparatus.

15 The object of my invention is to provide or produce a simple, cheap, and effective form of derrick-swingers which may be located at any desired position in respect to the hoisting-machine, on the same bed or skids, if desired, or independently thereof, and arranged to be driven by a flexible connection with the shaft of one of the drums of the hoisting apparatus—as, for instance, by an endless-chain connection between the two.

20 To accomplish all of the foregoing objects and to secure other and further advantages in the matters of construction, application, operation, and use, my improvements involve certain new and useful arrangements 25 or combinations of parts and particular features of construction, as will be herein first fully described and then pointed out in the claims.

25 In the accompanying drawings, forming part of this specification, Figure 1 is a plan or top view showing my improved derrick-swingers in position for use in connection with and arranged to be driven from the shaft of one of the drums of a hoisting apparatus. Fig. 2 is

30 a side view corresponding with Fig. 1, but showing the swinger mounted upon the same platform or skids as the hoisting apparatus.

35 Fig. 3 is a sectional elevation on a plane through line 3 3 of Fig. 1 looking in the direction of the contiguous arrow and on a larger scale, showing the manner of driving the winches or drums for the swinging rope or cable.

In all the figures like letters of reference wherever they occur indicate corresponding parts.

55 A is the shaft of the derrick-swingers, the same being suitably journaled in side frames, as B and C, on a suitable bed plate or frame, the said shaft carrying two winches or drums, 60 as D and E, for the swinging rope or cable. Each of the drums D and E are mounted so as to turn upon the shaft A and so as to be compelled to turn therewith when required. The connection of drums D and E with shaft A 65 is accomplished by means of planetary wheels and gears, one set for each winch or drum, and these gears are thrown into or out of action alternately, as will be hereinafter explained.

70 The planetary gearing is represented in Fig. 3, wherein the planetary wheel a, formed on the interior of the winch, engages the two gears or pinions b and c, the latter being extended within the winch or drum upon suitable studs d and e, of ample strength and durability, applied on the interior of the friction band-wheel a'. The gears or pinions b and c intermesh with a pinion f, keyed upon the shaft A. Friction-bands, as F and G, are applied in connection with the friction- 80 band wheels and arranged to operate alternately, being connected with a shaft, as H, movable by means of a hand-lever I, operating in connection with a suitable quadrant, as K. The arrangement of the parts is pref- 85 erably such that when the lever I is in a vertical position the bands F and G are loosened and the winches or drums D and E are therefore free to turn independently of the shaft A. By shifting the hand-lever I in either 90 direction from the vertical one of the friction-bands is tightened and the other further loosened, thereby compelling one of the drums or winches to turn with the shaft A and allowing the other to be moved in the op- 95 posite direction by the rope or cable which may be wound thereon.

100 L represents one of the drums of any of the usual forms of hoisting apparatus, the same being mounted on a drum-shaft M.

It is from one of the drum-shafts of the hoisting apparatus that I obtain the power for driving the derrick-swingers, and I preferably obtain this power from the shaft of the lower drum of the hoisting apparatus. Upon 105 this shaft I secure a suitable driving-wheel,

which under the arrangement shown in the drawings is in the form of a sprocket-wheel or chain-wheel, the teeth of which are represented at *g g*, and on the shaft *A*, I secure a 5 corresponding wheel, of which the teeth are represented at *h h*. These two wheels may be varied in construction according to the means employed for connecting them.

The two driving-wheels are connected by a 10 flexible medium, preferably in the form of an endless chain with rollers, as *N*; but instead of the chain any other suitable flexible means of connecting the two wheels may be employed—as, for instance, a rope or cable or 15 belt.

By use of the chain or other flexible connection between the two driving-wheels I am 20 enabled to place the derrick-swinger at any convenient point with respect to the hoisting apparatus and without interfering with the latter. It may, if convenient, be mounted upon the same skids *O* as the hoisting apparatus, but not necessarily so. It may be placed at any convenient distance from the 25 hoisting apparatus and independently thereof, upon the same or a different level, and by use of the flexible connection I obviate the necessity of the derrick-swinger being accurately alined with respect to the hoisting 30 apparatus, as would be required with any rigid form of connecting means. The device may therefore be set up and made ready to operate by unskilled mechanics, which is an important advantage in the use of this class 35 of devices. Being separate and independent of the hoisting apparatus, the use of the latter independently of the swinger is in no manner interfered with, and the addition of the driving-wheel adds very little to the cost 40 of construction of the hoisting apparatus and practically nothing to its size.

When the derrick-swinger is in place and the flexible connection applied, the shaft *A* will be caused to rotate in unison with the 45 shaft *M*, and the winches for the swinging rope or cable may be caused to move in either direction or allowed to remain immovable by suitably adjusting the hand-lever *I*.

The improved device is easily and cheaply 50 constructed and admirably answers all the purposes or objects of the invention herein alluded to.

Having now fully described my invention,

what I claim as new herein, and desire to secure by Letters Patent, is—

1. In a derrick-swinger, the combination with the shaft thereof, of a driving-wheel secured on said shaft and a flexible connection between the said driving-wheel and the shaft from which the driving power is derived, the 60 two shafts being arranged to turn together substantially as set forth.

2. In a derrick-swinger, the combination with the shaft, thereof, of a driving-wheel secured on said shaft, a flexible connection between said driving-wheel and the shaft from which the driving power is derived, and means for alternately clutching the winch-drums with the shaft of the derrick-swinger, the winch-drums being loosely mounted on 70 said shaft, substantially as set forth.

3. The combination with a hoisting apparatus, of a derrick-swinger, a driving-wheel secured upon the shaft of one of the hoisting-drums, a corresponding wheel applied directly upon the shaft of the derrick-swinger, and an endless flexible connection between the two wheels, substantially as and for the 75 purposes set forth.

4. The combination with a hoisting apparatus, of a derrick-swinger having drums movably mounted upon its shaft, a chain-wheel applied upon the shaft of one of the hoisting-drums, a chain-wheel secured directly upon the shaft of the derrick-swinger, 85 and an endless chain connecting the two chain-wheels, substantially as and for the purposes set forth.

5. The herein-described derrick-swinger comprising a shaft, two winches or drums 90 movably mounted on said shaft, means for alternately coupling the said drums with the shaft, and means for flexibly connecting the said shaft directly with the source of driving power therefor, the said derrick-swinger being arranged to be mounted in place for operation, substantially as and for the purposes set forth.

In testimony whereof I have signed my name to this specification in the presence of 100 two subscribing witnesses.

GUST. P. WERN.
